UNITED STATES PATENT OFFICE.

NATHAN H. HEFT, OF VALLEY, NEW JERSEY.

LUBRICATOR.

SPECIFICATION forming part of Letters Patent No. 295,757, dated March 25, 1884.

Application filed September 11, 1883. (No model.)

To all whom it may concern:

Be it known that I, NATHAN H. HEFT, of Valley, in the county of Hunterdon and State of New Jersey, have invented certain new and useful Improvements in Lubricators, of which the following is a specification.

My invention relates to that class of lubricators (adapted for use with stationary, locomotive, and other engines) which are automatic in their action, and in which the oil is fed in regulated quantities to the steam-pipe, whence the oil, mixed with the steam, is conveyed to the steam chest, cylinders, or other point of application.

15 The operation of my lubricator is dependent upon steam-pressure.

In the accompanying drawings, Figure 1 is a vertical longitudinal section of the lubricator. Figs. 2, 3, and 4 represent detached 20 details.

Similar letters of reference indicate similar parts in the respective figures.

A is the oil cup or chamber, having a head or cap, *a*, and filling-opening *A'*, the cap being united with the bottom of the cup by means of the bolt *b*, the upper end of the bolt being screwed into the boss *c*, formed as a part of the cap *a*. The lower end of the bolt is also threaded, and receives a nut, *d*, which embodies or fits against the lower collar, *d'*, of the cup. In the bolt *b* is cored a channel, *e*, communicating at *e'* with the interior of the cup *A*. The channel *e*, at its upper end, unites with a channel, *e''*, cored in a part of the cap *a*, which forms a shank or connection, *B*. A screw-valve, *B'*, is provided in the port, being seated in a thimble, *a'*, which is packed by a nut, *a''*. Within the shank *B* is a channel, *e'''*, which leads directly into the steam-pipe *C*, the shank being tapped into the pipe, as shown. The lower end of the bolt is provided with a horizontal aperture, *f*, leading to the vertical aperture *f'*, which communicates with the interior of the drip or blow-off cock *g*, formed as a part of the nut *d*.

At the upper part of the cup *A*, and detachably secured to the under side of the cap *a*, is a device used for refining and filtering the oil before its passage to the parts to be lubricated, the office and operation of which are hereinafter fully described.

The refining and filtering devices consist of a box, *h*, (see particularly Figs. 2 and 3,) of any desired or suitable shape, having its bottom and sides, or any part thereof, made open or in skeleton-work, so as to admit oil to the interior of the box. The top of the box is preferably closed, to prevent the necessity of forming a ground or close joint between the box and the under side of the cap; but, if desired, the top of the box may be open. The open bottom and sides of the box are covered with a delicate metallic gauze, *i*, which is then overlaid by one or more thicknesses of felt, *i'*, or other filtering material, which in turn is covered by another thickness of gauze, *i''*, the whole being covered by open plates *i'''*, secured by screws *i''''*. The plates may, however, be differently attached.

The box *h* is secured to the under surface of the cap *a* by a central bolt, *k*, or other suitable means. The bolt *k* is provided with a port, *k'*, which communicates with a port, *k''*, in the shank *B*, which port *k''* continues through the depending branch *k'''*, cast as a part of the shank *B*. The lower end of the branch *k'''* extends horizontally at *k''*. At the top of the part *k''* is a neck, *l*, in which is a port, *l'*, which, at its upper end, is reduced to minute dimensions—say one-sixteenth of an inch. The lower end of the port is of substantially the same area as that of the port *k''*. The main regulating-valve for controlling the flow of the lubricant to the engine is represented by *m*, the screw-valve being situated under the horizontal branch *k''*. The screw-valve *m* works in a thimble, *m'*, which is tapped into the branch *k''*, and upon the thimble *m'* is a packing-nut, *n*, a flexible washer being interposed, as shown by *n'*. The screw valve-stem is provided with a conical point, which seats at the bottom of the port *l'*.

As a part of, and above, the neck *l* is cast a vessel, *o*, it being connected to the shank *B* by the neck *o'*. Each side of the vessel *o* is open, and has a pane of glass, *o''*, inserted therein and secured by a nut, *o'''*. (See Fig. 4.) The panes are suitably packed to make a steam-joint. The interior of the chamber communicates by means of a port, *o''*, with the interior of the shank *B*. The outer end of the horizontal portion of the port *o''* is provided

with an inverted conical seat, o^5 , receiving the end of a screw-valve, o^6 , which screws in a thimble, o^7 , packed by a nut, p . The port o^4 continues past the valve o^6 and leads directly 5 into the steam-pipe. The length of the thread on the shank B is such as to allow the shank to be carried within to the center of the steam-pipe, so as to bring the port o^4 , as also the port e'' , centrally of the column of steam.

10 The operation of my invention is as follows: The cup is first charged with oil, the valves B' and m being closed. The port e'' is arranged to confront and meet the steam flowing from the boiler to the engine. The valve B' is now 15 opened to its full capacity, and steam at full boiler-pressure enters the cup and mixes with the oil, the oil being immediately brought to a state of ebullition. The steam is held back in the cup by the resistance of the filtering 20 medium in the box h , before described. Owing to the course of the steam through the steam-pipe, there is a less pressure at the exit of the port o^4 than in the port e'' , or any part of the apparatus below the box h , to which the steam 25 finds unobstructed entrance, and because of the obstruction by the filtering material and the fact that the mouth of the port o^4 is not in the course of the steam there is a minus pressure between the box h and the outlet o^4 .

30 Consequently the oil is forced by the excess of pressure through the ports k'' and l' , the chamber o , and port o^4 to the steam-pipe, it being understood that the flow is regulated by opening the valve m , the valve o^6 being at all 35 ordinary times open. The passage of the oil through the vessel o may be readily observed, the water of condensation which collects in the vessel serving as the medium through which the oil passes to the point of application.

40 As the operation of this lubricator depends upon the supply of steam to the engine, and the consequent inequality of pressure in the different parts of the apparatus, it will be seen that so soon as the steam is shut off from the 45 engine and the flow of the steam through the steam-pipe stopped the lubricator will cease to work, the pressure upon all its parts and throughout all its connections being immediately equalized. The heating of the oil up to 50 the full temperature of the boiler-steam has

the effect of vaporizing the constituents of the oil and of refining and elevating its grade, and also causes the separation and deposition of the sediment, which is carried off with the water of condensation through the cock g . 55 The oil which passes to the engine mixed with the steam is filtered and improved in quality.

The lubricator cannot become clogged in its working, and the points of leakage are reduced to the minimum by virtue of the small 60 number of joints.

Having described my invention, I claim—

1. The within-described method of lubricating, consisting in admitting steam under boiler-pressure to a body of oil and forcing the oil 65 through an obstructing body or filtering medium placed in the exit-port by the difference in steam-pressure existing at the two sides of said obstructing body, as set forth.

2. The within-described method of lubrication, consisting in forcing oil to the point of application by subjecting different parts of the apparatus and its connections to unequal steam-pressures. 70

3. The combination of an oil-cup having a 75 port leading thereto from the steam-pipe, a box, and a filtering medium, said box having a port leading therefrom to said steam-pipe, substantially as set forth.

4. The combination of an oil-cup having a 80 port leading to its lower end from the steam-pipe, a box and filtering medium at the upper part of the cup, having a port leading therefrom, a transparent vessel in said port, and having a port leading to the steam-pipe, and 85 suitable valves, substantially as set forth.

5. The lubricator-cup combined with the box h , having open sides, and a suitable filtering material, substantially as set forth.

6. The lubricator-cup combined with the 90 box h , having open sides, and a filtering medium, and gauze, substantially as set forth.

In testimony whereof I have hereunto set my hand and seal this 4th day of September, 1883.

NATHAN H. HEFT. [L. S.]
